UNITED STATES PATENT OFFICE.

JOHN FLAMMANG, OF UNIVERSITY CITY, AND PERCY L. BOWSER, OF ST. LOUIS, MISSOURI, ASSIGNORS TO STERLING PRODUCTS CORPORATION, OF ST. LOUIS, MISSOURI, A CORPORATION OF MISSOURI.

METHOD AND APPARATUS FOR CASTING TRUNK PISTONS.

Application filed February 18, 1924. Serial No. 693,512.

To all whom it may concern:

Be it known that we, JOHN FLAMMANG and PERCY L. BOWSER, both citizens of the United States, and residing, respectively, at University City, county of St. Louis, Missouri, and St. Louis, Missouri, have invented the new and useful Improvement in Methods and Apparatus for Casting Trunk Pistons, of which the following is a specification.

This invention relates to piston molds, and more particularly to molds used for die casting pistons of aluminum and similar metals and alloys.

According to the present method of casting pistons of this class, a metal mold is provided having a sectional core. After the casting metal has been poured into the mold and solidified, the core sections are withdrawn from the casting, after which the casting is taken from the mold. In these operations the removal of the core sections is done manually, the sections being removed one at a time, after which the casting is removed from the mold. In order to facilitate operation of this sort, the piston is cast with the head down, so that the core sections may be removed from the top.

The manual handling of a multiplicity of core sections for each mold together with the manual removal of the piston from the mold renders this method one which requires a considerable amount of time for the casting of a single article.

One of the objects of this invention, therefore, is to provide a method and apparatus for casting trunk pistons which shall facilitate handling of the various parts.

Another object of this invention is to provide an apparatus wherein manual operation of the parts is reduced to a minimum.

Another object of this invention is to provide such an apparatus which can be handled rapidly so as to reduce the time consumed in making a casting.

Another object of this invention is to provide an apparatus which shall be simple in construction, cheap to manufacture, and reliable in service.

Further objects will appear from the detail description taken in connection with the accompanying drawings, in which:

Figure 1 is a plan view illustrating an apparatus embodying this invention;

Figure 2 is a side elevation of Figure 1; 55
Figure 3 is a section on line 3—3, Figure 1;

Figure 4 is a section on line 4—4, Figure 1;

Figure 5 is a plan view with the mold part removed; 60

Figure 6 is a detail of the central core section;

Figure 7 is a detail of one of the side core sections; 65

Figure 8 is a view similar to Figure 3, taken on line 8—8, Figure 1;

Figure 9 is a view similar to Figure 4 but with the central core section lowered to free the casting; 70

Figure 10 is a section on line 10—10, Figure 11;

Figure 11 is a view similar to Figure 9 showing the mold in process of removal; 75

Figure 12 is a cross-sectional view of the completed piston casting.

Referring to the accompanying drawing 1 designates a table mounted on legs 2 and provided with an opening 3 in the top thereof. On the table 1 is mounted a base or support 4 provided with a pair of depending brackets 5 extending downwardly through the opening 3. Upon the support 4 is a plate 6 provided with a shoulder 7 adapted to receive and position a mold 8. The mold 8 is made in two sections, as illustrated in Figure 1, and the separate sections are provided with handles 9 for manipulating the same. A top or cover 10 closes the upper end of the mold cavity in the mold 8. The two sections of the mold 8 when in position on the shoulder 7 are held together by a pair of strong springs 11.

The plate 6 is provided with a cylindrical bore 12 within which are fitted a series of core sections. The support 4 is provided with arcuate guide-ways 13, each adapted to receive a guiding shoulder 14 on one of the side core sections 15. Each core section 15 has attached thereto a rod 16 extending laterally through a slot 17 in the plate 6. Each rod is encircled by a spring 18 bearing against a washer 19 on the outside of the plate 6 and against a handle 20 on the end of the rod 16. The spring 18 serves to hold the core section 15 with its shoulder 14 in engagement with a guide 13, but at the same

time to permit angular movement of the core section along the guide 18 when the handle 20 is swung laterally, the rod 16 moving in the slot 17 during such angular movement. The side core sections 15 are thus mounted for movement in the base so that they may be disengaged from the casting.

These side core sections are shown in detail in Figure 7 and are provided in two pairs. The sections of each pair are alike, except that they constitute right and left hand members. As illustrated in Figure 7, the faces 21 of the two sections of a pair abut against each other when in casting position. Each section is provided with a cavity 22 for molding the wrist pin bearings, each section of a pair forming half of the bearing. Each section may also be provided with a depression 23 for forming a reinforcing rib 24 on the finished casting, see Figure 12.

A central core section 25 is illustrated in detail in Figure 6. This section is provided with an outermost cylindrical surface 26 for forming the interior of the piston skirt. A similar surface is formed on the outer portion of the sections 15 (not shown in Figure 7) to form a continuation of the surface 26 when all of the sections are in assembled relation. The core section 25 is provided with a depression 27 on each side thereof into which one pair of side sections 15 fits when the cores are in assembled relation. A groove 28 may be provided to form a continuation of the cavity 22 in the side sections for molding the rib 24. Shoulders 29 on the core section 27 are adapted to close the lower opening of the mold cavity.

The central core section 26 is mounted on a rod 30 adapted to slide vertically in a bearing 31 on the brackets 5. To the rod 30 is fixed a block 32 which has pivoted thereto at 33 a pair of plates 34 connected to a pair of links 35 pivoted at 36 on the brackets 5. Two plates 34 are provided which are joined by a block 37 carrying a manipulative handle 38. The plates 34 together with the pivoted links 35 form a toggle which may be manipulated by means of a handle 38 so as to raise and lower the rod 30 and for forcibly withdrawing the central core section 25. The rod 30 is counter-balanced by a lever 39 pivoted at 40 to any suitable support, such as the floor, and carrying at its other end a counter-weight 41. It is seen that by raising the handle 38 the toggle formed by the plates 34 and the links 35 will be straightened, thereby drawing the block 32 downwardly so as to draw the central core section 25 downwardly out of the mold. When the core section 25 has been withdrawn from the mold, sufficient space is left so that the sections 15 of each pair may be separated and adjacent sections of different parts swung to-

gether into the space left by this central core section, and when so positioned, the core sections 15 are entirely clear of the wrist pin bearings formed by the recesses 22. When the core sections 15 are in this position, the casting may be removed therefrom by lifting the same vertically.

The mold 8 is formed in two half parts adapted to fit together to form the complete mold. Each half part is provided with two handles 9 which project substantially in opposite directions therefrom. The handles of different parts are thus positioned close together on each side of the mold so that each pair may be grasped by an operator in order to remove the mold. The mold may be provided with an opening 42 adapted to provide a gate for pouring the casting metal into the mold.

The operation of this device is as follows: The side sections 15 are swung together by moving the handles 20 so as to swing both sections together in pairs so as to complete the cavities 22 and 23. The central core section 25 may now be raised so as to occupy its position between the sections 15 so as to cooperate with them in forming the interior of the mold. This is done by manipulating the handle 38 so as to operate the toggle to raise the rod 30 and carry the section 25 into its place. The mold 8 may now be placed over the assembled core sections. This is done by two operators at the handles 9. The mold is placed in position with the half portions registering with each other and properly seated on the shoulder 7. Registry is insured by means of dowels 43. When the half parts are in place the springs 11 will press them firmly together against any possibility of separation when the metal is poured into the mold. An operator may now pour the casting metal into the mold by way of the gate 42 until the entire cavity is filled with the metal.

As soon as the cast metal has set sufficiently to maintain its shape, the handle 38 may be operated to drop the central core section 25. The handles 20 are then manipulated so as to swing the side core sections 15 clear of the wrist pin bearings of the casting. The handles 9 are then grasped by two operators and the mold with the casting therein is removed from the table. The casting may thus be transferred to any suitable place for cooling. In depositing the casting upon the cooling table, the same is released from the mold by pulling the half parts apart by means of the handles 9 by operators pulling simultaneously as the casting is set down. This leaves a casting of the shape illustrated in Figure 12. The sprue 44 may be removed by subsequent operation.

It will be seen, therefore, that this invention provides means for casting pistons of this type with great convenience and

rapidity. All parts of the sectional core which must be handled with some care so as to assure their assembly in proper relation to each other are permanently mounted on suitable supports, so that such assembly may be carried out by mechanical operation rather than by manual manipulation. Consequently the accurate and rapid assembly and disassembly of these parts is insured, regardless of the skill or proficiency of the operator. Mounting these parts for movement on their supports not only makes it possible to operate with great rapidity, but also provides that the operations may be carried out by unskilled operators, the guides on the supports in which the sections move being adapted to insure their movement in proper relation to each other. As soon as the side core sections are moved to assembled relation for casting, the central section may be inserted by a simple movement of the handle 38 and without any care or deliberation on the part of the operator. Similarly in handling the finished casting, the core sections may be disassembled with great rapidity without danger of injury to the casting, and the casting itself is then moved immediately by a single movement to a place for cooling and deposited by a simple movement.

It will be noted that the arrangement by which the piston is cast with the head up instead of the usual method with the head down, makes it convenient to mount the core sections for mechanical operation. Providing a mold which takes over the core sections makes it a simple operation to handle the finished casting while still within the mold after the core sections have been disengaged. It will be seen, therefore, that all these improvements make for great rapidity and accuracy in casting pistons of this kind.

It is obvious that various changes may be made in details of construction without departing from the spirit of this invention; it is, therefore, to be understood that this invention is not to be limited to the specific details shown and described.

Having thus described the invention, what is claimed is:

1. An apparatus for casting trunk pistons, comprising, a support, a plurality of core sections mounted on said support, and means for moving each of said sections into assembled relation for casting and into disassembled relation for removal of the casting.
2. An apparatus for casting trunk pistons comprising, a support, a plurality of core sections including a central and side sections mounted on said support, guides for said sections, and means for moving said sections along said guides into assembled relation for casting and into disassembled relation for removal of the casting.

3. An apparatus for casting trunk pistons comprising, a support, a plurality of core sections each guided for movement on said support to assembled and disassembled relations, and means for moving said sections. 70

4. An apparatus for casting trunk pistons comprising, a support, a plurality of core sections guided for movement to assembled and disassembled relations, means for moving one of said sections, and means for moving another of said sections into the space left by the first moved section. 75

5. An apparatus for casting trunk pistons comprising, a support, a plurality of core sections each guided for movement to assembled and disassembled relations, means for forcibly withdrawing one of said sections, and means for moving another of said sections. 80

6. An apparatus for casting trunk pistons comprising, a support, a plurality of core sections each guided for movement to assembled and disassembled relations, means for moving said sections, and a mold taking over said core and completing the mold cavity. 85

7. An apparatus for casting trunk pistons comprising, a support, a plurality of core sections projecting upwardly from said support and each guided for movement to assembled and disassembled relations, and a mold taking over said core and completing the mold cavity. 90

8. An apparatus for casting trunk pistons comprising, a support, a plurality of core sections each guided for movement on said support, and a toggle for forcibly withdrawing certain of said sections. 100

9. An apparatus for casting trunk pistons comprising, a support, a plurality of core sections each guided for horizontal movement on said support, a central core section mounted for vertical movement on said support, and means for moving said sections. 105

10. An apparatus for casting trunk pistons comprising, a support, a plurality of core sections each guided for angular movement thereon, a central core section mounted for vertical movement on said support, and means for moving said sections. 115

11. An apparatus for casting trunk pistons comprising, a support, a plurality of core sections mounted for movement thereon, a guide on said support for guiding certain of said sections for angular movement, a guide for guiding another of said sections for vertical movement, and means for moving said sections. 120

12. An apparatus for casting trunk pistons comprising, a support, a plurality of core sections projecting upwardly on said support and movable thereon, a split mold adapted to take over said core to complete 130

- the mold cavity, and a manipulative element for said mold, whereby said mold may be manipulated to remove the casting from said core and thereafter to free the casting from 5 said mold.
13. In the art of casting trunk pistons, the method comprising, casting the piston over a sectional core with the head of the piston up, and removing the core sections down- 10 wardly from the casting.
14. In the art of casting trunk pistons, the method comprising, casting the piston over a sectional core with the head of the piston up, and lifting the casting vertically 15 from the core.
15. In the art of casting trunk pistons, the method comprising, casting the piston over a sectional core with the head of the piston up, lifting the casting vertically from the 20 core by means of the mold, and freeing the casting from the mold.
16. In the art of casting trunk pistons, the method comprising, casting the piston over a sectional core with the head of the piston up, shifting the core sections rela- 25 tively, and lifting the casting vertically from the core.
17. In the art of casting trunk pistons, the method comprising, casting the piston over a sectional core with the head of the piston up, disengaging the core sections from 30 the interior projections, and lifting the casting vertically from the core.
18. In the art of casting trunk pistons, the method comprising, casting the piston over a sectional core with the head of the piston up, removing one of the core sections, shifting another core section into the 35 space left by the removed section, and lifting the casting vertically from the core.
19. In the art of casting trunk pistons, the method comprising, casting the piston over a sectional core with the head of the piston up, removing one of the core sections 40 downwardly from the casting, and shifting another core section into the space left by the removed section.
20. In the art of casting trunk pistons, the method comprising, casting the piston over a sectional core with the head of the piston up, shifting the core sections relative- 45 ly, lifting the casting vertically from the core by means of the mold, and freeing the casting from the mold.
21. In the art of casting trunk pistons, the method comprising, casting the piston over a sectional core with the head of the piston up, disengaging the core sections 50 from the interior projections, lifting the casting vertically from the core by means of the mold, and freeing the casting from 55 the mold.
22. In the art of casting trunk pistons,
- the method comprising, casting the piston over a sectional core with the head of the 65 piston up, removing one of the core sections, shifting another core section into the space left by the removed section, lifting the casting vertically from the core by means of the mold, and freeing the casting from 70 the mold.
23. An apparatus for casting trunk pistons, comprising, a support, a plurality of core sections having recesses for forming the interior projection of the casting and 75 mounted on said support, and means for moving each of said sections into assembled relation for casting and into dissembled relation for clearing the casting projections in order to permit removal of the casting. 80
24. An apparatus for casting trunk pistons comprising, a support, a plurality of core sections each guided for movement on said support to assembled and dissembled relations, said sections having cooperative 85 recesses for forming the interior projection of the casting, and means for moving said sections.
25. An apparatus for casting trunk pistons comprising, a support, a plurality of 90 core sections each guided for movement to assembled and dissembled relations, means for moving said sections, and a mold taking over said core, said core and mold being constructed and arranged to form a mold 95 cavity for a piston with the head up.
26. An apparatus for casting trunk pistons comprising, a support, a plurality of core sections projecting upwardly from said support and each guided for movement to 100 assembled and dissembled relations, and a mold taking over said core, said core and mold being constructed and arranged to form a mold cavity for a piston with the head up. 105
27. An apparatus for casting trunk pistons comprising, a support, a plurality of core sections each guided for movement to assembled and dissembled relations, means for moving said sections, and a mold taking 110 over said core to complete the mold cavity and having a top adapted to form the head of the piston casting. 115
28. An apparatus for casting trunk pistons comprising, a support, a plurality of core sections projecting upwardly from said support and each guided for movement to assembled and dissembled relations, and a mold taking over said core to complete the mold cavity and having a top adapted to 120 form the head of the piston casting.

In testimony whereof we affix our signatures this 8th day of January, 1924.

JOHN FLAMMANG.
PERCY L. BOWSER,
